Patented Nov. 29, 1921.

UNITED STATES PATENT OFFICE.

OLIVER METCALF RICE, OF BIRMINGHAM, ALABAMA.

TOOL FOR DEMOUNTABLE RIMS.

1,398,801.

Specification of Letters Patent. Patented Nov. 29, 1921.

Application filed August 21, 1920. Serial No. 405,148.

To all whom it may concern:

Be it known that I, OLIVER M. RICE, a citizen of the United States, residing at Birmingham, in the county of Jefferson and State of Alabama, have invented certain new and useful Improvements in Tools for Demountable Rims; and I do hereby declare the following to be a full, clear, and exact description of the invention, such as will enable others skilled in the art to which it appertains to make and use the same.

The present invention relates to improvements in tools for demountable rims, and more particularly refers to an improved tool for contracting and expanding the demountable wheel rims of automobiles.

An object of the invention is to provide an improved construction of framework for the tool, and of clamps for engagement with the demountable rim to which the tool has connection for expanding and contracting same.

Another object of the invention lies in providing a compact and durable construction adapted to be placed within a demountable rim and to be supported at a suitable height so as to effectually act upon the rim at opposite sides of its cross-cut.

The invention will be more fully understood after reference to the accompanying drawings, in which like parts are indicated by similar reference symbols throughout the several views, and in which:—

Figure 1 is a side elevation of an improved tool constructed in accordance with the present invention and shown as applied to a rim indicated in dotted lines.

Fig. 2 is a plan view thereof with parts shown in section; and

Fig. 3 is a plan view thereof with the clamps removed, and with a portion of the handle broken away.

Referring more particularly to the drawings, 1 designates the base of the frame which is preferably formed in one piece of malleable metal, and which is formed of an open construction having the end posts 2 and 3 supporting the top rail 4. The frame is made interiorly with a brace 5, set inwardly a suitable distance from the end post 3 and providing a space between these two members in which to receive and confine a bevel pinion 6, which is provided with interior threads to engage a longitudinally

shiftable worm shaft 7, passing through 55 suitable plain openings made in both the end post 3 and brace 5.

The pinion 6 meshes with a bevel gear wheel 8, journaled on a stud 9 projecting from a plate 10, which is fitted against the frame at one side and adjacent the brace 5. The plate 10 is secured to the base 1 by rivets or other suitable fastenings 11, and is bent beneath the base into a substantially U-shaped guide 12 for slidably receiving the 65 bar 13. Pins 14 on or near the free end of the bar 13 are provided to engage the guide 12 at one side to avoid the withdrawing of the rod 13 therefrom. The rod is therefore free to slide back and forth beneath the 70 base 1 of the frame.

The end post 15 is bent upwardly from the other end of the bar 13 and is provided with an opening to receive the reduced end 16 of the worm shaft 7, said end being secured therein as by a rivet 17 to prevent the shaft from turning.

The upper end of the post 15 is bent substantially diagonally, as indicated at 18, and carries a pin 19 to engage with a perforation in the rim or in a clamp, as will be hereinafter described.

The top rail 4 of the frame is also cast or otherwise produced with a boss 20, which carries a pin 21 also for engaging an opening in the rim or in the companion clamp, as presently explained. The two adjacent ends of the rim are indicated at 22 and 23, and the rim cross-cut at 24. A handle 25 is employed to turn the bevel gear 8 and for 85 this purpose is mounted on the stud 9 as by a pin 26. This pin is preferably made so that it may be withdrawn and the handle removed to enable the device to be folded or compactly disassembled when placing the 90 same in the tool kit of the automobile. The handle may also be of a foldable variety to serve the same purpose.

The clamps above referred to are designated at 27 and 28, but inasmuch as they 100 are both of a similar construction but one need be described. Each clamp consists of an elongated, thin, substantially flat plate 29 of metal or other suitable material having an opening at one end to receive the 105 threaded shank 30 of a hook 31. Nuts 32 are adapted to bind the hook in place after it has been rotated to a suitable position.

The opposite end of the plate 29 is provided with an elongated slot 33 in which a similar threaded shank 34 of a hook 35 is fitted, lock nuts 36 being employed at opposite sides of the plate to hold the hook in the adjusted position.

Centrally the plate 29 is provided with a perforation to receive either the pins 19 or 21 accordingly as the clamp is used at one or the other side of the cross-cut 24 of the rim. On the side of the plate 29 next the rim and formed about the central opening are a pair of bosses 37 and 38 of a curved construction approaching a circle, being struck from the center of the opening.

A foot piece 39 made of a piece of strap metal or other suitable material, bent into a substantially rectangular shape, is connected by rivets or other suitable fastening 20 40 to the U-shaped guide 12 at that side of the frame opposite to the plate 10.

In use the rim is laid out horizontally on the ground or supporting surface, and if the same is not provided with openings 25 the clamps 27 and 28 are applied thereto in the manner shown in Fig. 1. The hooks 31 and 35 are engaged over the flanges of the rim, the slot 33 permitting the adjustment of said hooks to fit rims of different widths. 30 The threaded shanks 30 and 34 also allow the hooks to be adjusted toward or from the body portion of the plate 29 to accommodate flanges of various thickness.

The clamp in the form shown will allow 35 of its connection to all standard forms of demountable rims. After the clamps have been set in place at opposite sides of the cross-cut 24 the tool is set within the rim, being allowed to rest upon the foot piece 39 40 which holds it at the required elevation, permitting the pins 19 and 21 to enter the central openings in the clamps.

The handle 25 is thereupon turned, imparting rotation to the bevel gear wheel 8. 45 This latter gear wheel 8 with the pinion 6 will impart rotary motion thereto which will result in the feeding of the shaft 7 longitudinally through the frame. Upon returning the handle in a proper direction 50 the shaft 7 will be fed outwardly, thus carrying the bar 13 and post 15 away from the end post 3 of the frame.

It will be understood that this movement is accompanied by a spreading of the 55 rim ends 22 and 23 and an opening of the rim at the cross-cut 24. A suitable implement may be used to pry the rim out of alinement at the cross-cut, and the handle 25 may then be rotated in an opposite direction to cause a collapse of the rim. In the collapsed condition the tire may be readily removed and a fresh tire replaced, after which the rim is expanded in a manner which will now be well understood.

65 The hook 41 is pivoted on a pin 42 passing

through the post 20, and a similar hook 43 is flexibly carried by a chain 44 secured to the post 15. These latter hooks may or may not be mounted in conjunction with the remaining parts, but they will act to engage with the 70 sides of the rim and to draw the same out of alinement or to engage directly with openings in the rim, or with parts of the clamps which are set at more widely separated points, not shown in Figs. 1 and 2.

75 The tool may be used for breaking the rim by placing the same substantially diametrically across such rim with the point 1 engaging the inner surface of the rim and with the hook 41 engaged over one of the 80 flanges of such rim. The hook 43 will be engaged over the flange of the rim at a point thereof opposite that at which the hook 41 engages. With the tool in this position a sharp pull upon the same or a partially 85 quick rotation thereof will cause the rim ends to be pulled past each other at the joint so as to put the rim into condition to be contracted. Then again where rims are very stiff the hooks 41 and 43 are used in 90 combination with the pins so as to have a double engagement with the rim.

95 Of course the clamps are not necessary where holes for the pins 12 and 19 are drilled directly in the rim; the clamps are, however, useful where the rims have not as yet been provided with such holes, the idea being to furnish purchasers of the tool with clamps until they are able to have their rims drilled with the necessary holes to receive the pins. 100

105 It will be obvious that various modifications might be made in the herein described apparatus, and in the construction, combination and arrangement of parts which could be used without departing from the spirit of my invention; and I do not mean to limit the invention to such details except as particularly pointed out in the claims.

Having thus described my invention what I claim and desire to secure by Letters Patent of the United States is:—

110 1. A tool of the character described comprising a pair of clamps adapted to be secured at opposite sides of the cross-cut of a rim, and each composed of elongated plates having openings therein, hooks adjustably carried by said plates and adapted to fit about the flanges of the rim, a frame adapted to rest within the rim, a pin on said frame engageable with the opening in one of 115 said clamps, a second pin movable with respect to the frame, and adapted to fit in the opening of the other clamp, and means for causing the separation of said pins and their movement together, substantially as described.

120 2. A tool of the character described comprising a pair of clamps adapted to embrace the rim at opposite sides of its cross-cut, said clamps having intermediate and end open- 125

ings therein, hooks carried by the end openings, pins for receiving the intermediate openings, and means to move said pins apart and toward each other, substantially as described.

3. A device of the class described comprising a pair of clamps associated for relative movement and including adjustably disposed coöperating hooks, relatively movable pins 10 detachably connected with said clamps, and manually operable gear mechanism for shifting said pins apart and together substantially as described.

4. A device of the kind described comprising clamps having openings with curved and raised bosses extending thereabout adapted to engage the interior surface of the rim, hooks carried by said clamps for engaging the sides of the rim, and means for shift-

ing the clamps upward and away from each other substantially as described.

5. A tool for use in connection with demountable rims comprising a frame, a guard extending beneath the frame and at the sides thereof, a foot piece secured to the guard at one side of the frame, a bevel gear wheel journaled on the guard at its opposite side, a bar sliding relatively to the frame within the guard, a screw shaft attached to the bar and movable through the frame, a pinion 25 having internal engagement with the spiral shaft and external engagement with said gear, a detachable handle to turn the gear, and clamps carried respectively by the frame and said bar for engaging with the wheel 30 rim substantially as described.

OLIVER METCALF RICE.
